WILLIAM F. LAUTENSCHLAGER, OF CINCINNATI, OHIO, ASSIGNOR TO LORENZ MUNTER,
OF NEWTON, MASSACHUSETTS.

FOLDING-MACHINE.

1,301,718.

Specification of Letters Patent. Patented Apr. 22, 1919.

Application filed June 26, 1916. Serial No. 195,928.

To all whom it may concern:

Be it known that I, WILLIAM F. LAUTENSCHLAGER, a citizen of the United States, residing at Cincinnati, in the county of Hamilton and State of Ohio, have invented certain new and useful Improvements in Folding-Machines, of which the following is a specification.

This invention relates to folding machines for folding over the edges of materials and more especially for folding over the edges of shoe parts used in the manufacture of boots and shoes.

Heretofore in the use of folding machines for folding over the edges of shoe vamps it has been customary, as a general rule, to fold the vamps while in an open condition, that is, without being closed at the heel seam. When open vamps are folded the work can be fed through the folding machine in a flat condition, which facilitates the folding operation without twisting or stretching the leather and enables the operator to secure a smooth, clean fold, especially around curved portions of the vamp, such as the throat. When the vamps are folded in an open condition, however, they are folded to within a short distance of each end and the vamp is then closed at the heel seam, after which that portion of the edge at the heel seam is folded by hand.

In some cases, however, vamps have been first closed at the heel seam by being stayed and stitched and machines have been provided for folding vamps after being closed so as to complete the folding of the entire edge of the closed vamp in one operation. In machines of this character the folding instrumentalities have been arranged within a small compass with a narrow work support which permitted the closed vamp when turned inside out to be placed over the narrow support and then folded continuously. The folding of the closed vamps on machines of this character has been open to one serious objection and that is that it has been difficult to secure a smooth, even fold on the curves of small radii, especially at the throat of the vamp, because when these points are reached in the vamp it is necessary to hold the material or vamp in a strained position which tends to stretch the leather and prevent an even, smooth fold being laid by the machine.

The main object of my invention is to provide a folding machine of simple construction adapted to fold closed vamps and similar work while the vamp is held in a substantially flat position at the time that the machine is operating upon curved portions of the work, that is, those portions at the throat of the vamp and to this end I provide a machine having a flat work support and an over-hanging arm above the work support and means whereby the folding instrumentalities carried on the over-hanging arm may be raised at the will of the operator without interfering with the operation of the machine in order to permit work in the form of an endless band to be passed between the work support and the folding instrumentalities on the overhanging arm into the space between the work table and the overhanging arm.

Another object of the invention is to provide a folding machine in which the folding instrumentalities are so formed and arranged that the edge of the material which is being folded is curled over naturally and pressed down without being strained or forced out of the line of a natural curve by any of the folding instrumentalities.

An additional object of the invention is to provide a folding machine which is evenly balanced and can be operated at a very high speed without appreciable noise or vibration.

Other objects of the invention will be more specifically set forth and described hereinafter.

In the accompanying drawings illustrating the preferred embodiment of my invention, Figure 1 is a side elevation of a folding machine constructed and operated in accordance with my invention as viewed from the position occupied by an operator of the machine;

Fig. 2 is a plan view of the same on line 2-2 in Fig. 1;

Fig. 3 is an end view partly in elevation and partly in section on line 3-3 in Fig. 1 looking from left to right;

Fig. 4 is a sectional view on line 4-4 in Fig. 3;

Fig. 5 is a side elevation of the power end of the machine looking toward the operator;

Fig. 6 is a sectional view, on an enlarged scale, on line 6-6 in Fig. 1 looking from left to right;

Fig. 7 is a view in perspective illustrating the use of the machine in folding a closed vamp and showing the position of the vamp when the machine is operating upon the 5 throat of the vamp; and,

Fig. 8 is a view in perspective of a group of some of the folding instrumentalities.

In the drawings illustrating the preferred embodiment of my invention is shown a machine comprising a frame made up of a standard 10 the upper portion of which is turned over horizontally to form an overhanging arm 11. On the lower portion of the standard 10 is a projecting arm 12 in 15 vertical alinement with the overhanging arm 11. Upon the ends of the overhanging arm 11 and lower arm 12 are mounted the folding instrumentalities. The end of the lower arm 12 is divided to form a closed yoke 14 20 mounted by a work-support 15 and within the space inclosed by said yoke is mounted such of the folding instrumentalities as are carried by the lower arm.

A suitable work table 16 is also carried by 25 the lower arm and is preferably made in two parts as shown in Fig. 2 so that it may be removed when desired in order that the machine may be used as a cylinder arm machine with a narrow work-support. The portion 30 of the work table 16 directly under the overhanging arm is preferably depressed, see Fig. 1, and lower than the portion of the work table surrounding the folding instrumentalities. This feature permits the portion 35 of the work not being operated on by the folding instrumentalities to be moved freely between the overhanging arm and the operating mechanism thereon on the one hand and the work table on the other hand 40 and is of special advantage when closed vanps are being folded as illustrated in Fig. 7 to be described in detail hereafter.

The folding instrumentalities consist of a gage 17 for guiding the work through the 45 machine, a fold-turner or plow 18 for turning over the edge of the work to be folded, a feed bar 19 for feeding the work forwardly, a presser-foot 20 for holding the work between the feeding movements and a 50 fold-presser 21 for pressing the folded edge down upon the body of the material being folded. Means are also provided for slitting the edge to be folded whenever desired, said means comprising a sliding lower knife 55 block 23 and an upper movable knife 24 cooperating therewith. The feeding bar 19 and presser foot 20 are preferably mounted upon the overhanging arm 11 and the remainder of the folding instrumentalities are 60 carried by the lower arm 12 and within the yoke 14.

The gage 17 is in the form of an arm secured to a depression in the work support by a screw 26 passing through a slot in the

gage which permits the gage to be adjusted 65 into the desired position with its guiding face 27 adapted to engage the edge of the work being folded.

The fold-turner or plow 18 may be of any suitable form but as shown is a block fastened to the work support and having an oblique curved face which is presented to the edge of the work to turn it upwardly as it is fed forwardly. The plow is located just beyond the guide with a space between the 70 two sufficient to permit of the insertion of a movable cutting knife (to be hereinafter described) for slitting the edge to be folded when desired.

The means for feeding the work through 80 the machine consists of the feed-bar 19 movable in a feed-housing 30. The lower end of the feed-bar is in the form of a foot 31 provided on its under surface with teeth to grip the work. Coöperating with the feed-bar is a feed-block 32 arranged underneath the work support and supported on rollers 33 carried by a depending bracket secured to the work support. The feed-block 32 moves freely on said rollers and is provided with 85 descending end projections which limit its movement. A spring 35 under compression tends to hold said feed-block in a retracted position; that is, toward the operator. The work support is provided with an opening 95 37 above and exposing a portion of the feed-block so that when the work is being fed the feed-foot 31 engages the work pressing it against the exposed surface of the feed-block 32 and the forward movement of the feed-foot 31 carries the work forward, moving the feed-block 32 in the same direction. When the feed-foot is released from the work the spring 35 forces the feed-block 100 back into normal position and ready for the 105 next feeding movement.

Attached to the feed-bar 19 is a laterally projecting finger or hold-down 39 which engages the edge of the work during the feeding operation and holds it against the gage 110 to insure feeding it evenly and to prevent any curling of the edge against the gage.

The presser-foot 20 which holds the work between the feeding movements is movably mounted in a presser-foot housing 40 carried by a plate 41 secured to the end of the overhanging arm 11. The lower end of the presser-foot 20 is bent, so that its lower end will engage the work at a point adjacent to the feeding engagement.

For operating the feeding means and the presser-foot, means are provided for moving the feed-bar downwardly into engagement with the work then forwardly to feed the same, then upwardly to release it from the 125 work, then rearwardly and downwardly to again engage the work for the feeding movement and means are provided for moving

the presser-foot downwardly to engage the work when the feed-bar reaches the end of its movement and to hold the work while the feed-bar is moving rearwardly to the 5 point of beginning of the next feeding movement, when the presser-foot is then raised. These means consist of a feed-shaft 45 and a lift-shaft 46 the former accomplishing the forward and rearward movement of the 10 feed-bar and the latter the upward and downward movement of both the feed-bar and the presser-foot. The feed-shaft 45 is journaled at one end in a bearing in the standard 10 and at the other end in a bearing 15 in the end of the overhanging arm 11, a collar 47 being secured to the shaft at the latter end to prevent longitudinal movement. The end of the feed-shaft 45 projects through the bearing on the end of the 20 arm 11 and is secured within a portion of the feed-housing 30 which is formed like a split collar, the end of the feed-shaft being secured within the split collar by a screw 48. In order to impart a forward and rearward 25 movement to the feed-bar the feed-shaft 45 is oscillated through suitable connections with the main shaft of the machine.

The main shaft 50 is mounted in suitable 30 bearings in the lower part of the standard 10 and the end of the lower arm 12 and projects through the yoke 14. Upon the power 35 end of the main shaft is mounted a suitable pulley 51 which may be driven by a belt from a transmitter not shown. Between the pulley and the standard 10 an eccentric is secured to the main shaft and this eccentric may be independent of or made a part of the pulley. Through the upper part of the standard 10 is journaled a rock-shaft 54 on 40 one end of which is mounted an arm 55. The end of this arm is connected to the main shaft by means of an arm 56 having its lower portion 57 in the form of a strap to inclose the eccentric adjacent the pulley 51 and its 45 upper end in the form of a yoke 58 to receive the end of the short arm 55 which is secured thereto by a pin 59. By these means the rotation of the main shaft and the eccentric through the connection just detailed imparts a rocking motion to the rock-shaft 54. The feed-shaft 45 is oscillated by the rock-shaft 55 through the following means: Upon the other end of the rock-shaft 54 is secured an arm 60 its upper end 61 being in the form of a collar to receive a pin 62 by means of which it is connected to a second arm 63, the latter in turn being connected at its lower end 65 to a similar arm 66 by means of a pin 67, a collar 68 being interposed between the 60 arms 63 and 66. The upper end of the arm 66 is in turn connected to an arm 70 by a pin 71; the arm 70 being secured to the feed-shaft 45. The arm 60 is fixed on the rock-shaft 54 and moves with it and the arm 70

is also fixed on the feed-shaft 45 and likewise moves with it but the arms 66 and 63 move independently of the arms 60 and 70 and independently of each other except in so far as they are restricted by the various pins connecting them. The end of the pin 70 71 is attached to a feed regulating lever 72 the lower end of which engages a slot 73 in a horizontal sliding bar 74 connected to a lever 75.

In operation the short arm 55 is moved 75 up and down when the main shaft is turned through the medium of the eccentric and the arm 56, thereby rocking the rock-shaft, oscillating the arm 60 and thereby the arm 63 which oscillates the feed-shaft 45 through 80 the medium of the connecting arms 66 and 70.

The oscillation of the feed-shaft 45 causes the feed housing to be swung forwardly and rearwardly with relation to the operator and 85 thereby imparts the forward and rearward movement of the feed-bar during the feeding operation.

The upward and downward movements of the feed-bar and presser-foot are accomplished by the lift-shaft 46 in the following manner. An eccentric 76 is mounted on the main shaft 50 and is inclosed by a strap 80 secured to an arm 81 having its upper end in the form of a yoke 82. Pivotedly connected to the yoke by a pin 83 is a link 84 having one end in the form of a yoke whereby the link is connected to a short arm 85 secured to the lift-shaft 46. The rotation of the main shaft through the medium of the 100 eccentric within the strap 80 imparts to the lift-shaft 46 an oscillating movement through the medium of the arm 81 and link 84. It will be noticed that normally the longitudinal axes of the arm 81 and the link 84 lie in 105 a line which is substantially straight.

For the purpose of raising the feed-bar and presser-foot sufficiently to permit a closed vamp or work in the form of an endless band to be inserted between these parts 110 and the work support and folding instrumentalities mounted thereon, I provide means for giving the lift-bar an additional oscillating movement during the operation of the machine without interfering with its 115 operation and at the will of the operator. For this purpose the pin 83, by which the link 84 is connected to the arm 81, is extended and has mounted thereon a short arm 88 pivotally connected to one end of a bell-crank lever 89, the other end of said lever being pivotally and loosely mounted on the feed-shaft 45. The bell-crank lever 89 is provided with a slot 90 through which the lift-shaft 46 passes and the purpose of this 120 slot is to limit the movement of the bell-crank lever. The bell-crank lever is also provided with an outwardly and upwardly

projecting arm 91 which may be connected by a rod 92 to a suitable treadle, not shown. When the treadle is depressed the rod 92 pulls the arm 91 downwardly thereby moving the bell-crank lever on its pivot, the shaft 45, and the arm 88 inwardly toward the operator, thereby causing the arm 85 to be moved downwardly and imparting an additional and further movement to the lift-shaft 46.

The lift-shaft 46 is connected to the feed-bar and presser-foot as follows:

Upon the end of the lift-shaft is secured a split collar 95 having a projecting arm 96 connected by a link 97 to a split collar 98 on the feed-bar in such a manner that any rocking movement of the lift-shaft lifts the feed-bar in the feed housing. Between the collar 98 and said housing is arranged a fibrous washer 100, preferably made of fibrous material so as to stand wear, and by regulating the position of the feed-bar in the collar 98 the position of the feed-bar can be adjusted to a fine degree so that the feed-foot will grip the material when in a feeding position without engaging the feed-block 32. The collar 95 on the end of the lift-shaft 46 is further provided with a downwardly and outwardly projecting arm 102 in the end of which is mounted an adjustable screw 103. When the lift-shaft is oscillated the screw 103 engages a pin 104 mounted in a bell-crank lever 105 pivotally mounted on an arm 106 projecting from the presser-foot housing 40, the lower end of the bell-crank lever 105 being pivotally connected to the lower end of a bar 108 which is connected at its upper end to a split collar 109 secured to the upper end of the presser-foot 20. By means of this connection the oscillation of the lift-shaft 46 operates to lift both the feed-bar and the presser-foot during the operation of the machine and at the required times. In the operation of the machine the feed-bar is lifted at the end of the feeding movement and is lowered just prior to the beginning of the feeding movement and the presser-foot is lowered at the end of the feeding movement to grip the material and raised at the beginning of the feeding movement to release the material. By adjusting the screw 103 the lifting and lowering of the presser-foot can be actually timed with respect to the feeding movement of the feed-bar.

For the purpose of raising the feed-bar and presser-foot an additional height in order to permit of the insertion of work between these elements and the work support during the operation of the machine, I provide on the collar 109 an extending arm 112 which extends over the collar 98 on the feed-bar 19 so that when the feed-bar is raised an additional distance by the operation of

the arm 91 the collar 98 engages the extension 112 and raises the presser-foot. It will be noticed that the extension 112 is normally sufficiently above the collar 98 so that the up and down movement of the feed-bar 19, during the normal feeding operation, does not interfere with the extension 112 and produces no effect upon the presser-foot. In order to maintain the feed-bar 19 and the presser-foot 20 in a lowermost position two springs are provided, 113 and 114 respectively. The amount of movement of the feed-bar and presser-foot when raised to permit of the insertion of work in the form of an endless band is determined by the length of the slot 90.

In Fig. 4 of the drawing, 21 represents the fold-presser, and 120 a bushing which is secured in an elongated hole 121 in the fold-presser, which bushing is mounted on the bearing shaft 122. The purpose of this elongated hole is so that the fold-presser may move up and down on the bushing 120 the fold-presser being held in the position shown in Fig. 4 by means of a spiral spring 123, one end of which bears and presses against the bearing bushing or sleeve 120, the other end against the end of an adjusting screw 125 which is threaded into the projecting part 127 of the fold-presser 21. The adjusting screw 125 is used to increase or decrease the tension of the spring 123.

The fold-presser 21 is provided with a movable fold pressing member 130. This fold-pressing member 130 is rectangular in form, so as to embrace the end of the fold-presser 21 and is held in position by the screws 131 and 132 which pass through slotted holes as shown in Fig. 2. This method of mounting the pressing member 130 on the fold-presser 21 permits of an endwise movement of the fold-pressing member 130 approximately longitudinally of the fold-presser 21. The fold-pressing member 130 is held in an inward position, as shown in Fig. 4, by means of a spring 134, one end of which is bent downwardly and is inserted in a hole in the fold-presser 21 and the other end is bent upwardly and inserted in the pressing member 130 so that the tension of the spring 134 will normally hold the fold-pressing member in an inward position, as shown in Fig. 4.

In using the term "normal position" I wish it understood that this term is intended to be used in connection with the positioning of the fold-pressing member 130 as illustrated in the drawings. The fold-pressing member 130 is provided with a rear curving portion 136 which is curved on a circle, the center of which is located at the axis of the bearing 122, as shown in Fig. 4, in order that when the fold-pressing member is thrown forward by the operation of a

lever 138 controlled by the operator, the rocking movement of the fold-presser will not cause the lever to vibrate.

In order to impart a rocking movement to the fold-presser to carry out the pressing operation thereof in successive steps, the following means are provided: Upon the end of the main shaft 50 is eccentrically mounted a stud 140 carrying on its free end loosely a block 141 having a pin 142 engaging a hole in one end of a bell-crank lever 143 mounted on a shaft 144. The pin 142 is movable in the end of the bell-crank lever 143 as the block 141 travels in a circular path when the main shaft 50 is revolved. The other end of the bell-crank lever 143 carries a pin 145 which is held therein in any desired position by a set-screw 146. The end 147 of this pin 145 is eccentric to the remaining portion of the pin, that is to those portions of the pin which are in the bell-crank lever and projecting on the other side thereof. By this combination I am enabled to change the location of the end 147 of the pin 145 by loosening the set-screw 146 and turning the pin in the bell-crank lever and then resetting the set-screw.

The eccentric end 147 of the pin 145 lies within a yoke 148 formed in the lower end 30 of the fold-presser 21. The result of this construction is that the bell-crank lever 143 is oscillated from the main shaft and thereby imparts an up and down movement of that part of the fold-presser carrying the fold-pressing member 130, in order to perform the pressing operation. As before stated, the pin 147 may be adjusted within certain limits and thereby the up and down path of the fold-pressing member is determined in order to prevent that member striking the work support when being operated. At the same time this construction permits of a very fine adjustment in this respect.

It will be noted that the fold-pressing member 130 is so formed that it has a cut away portion shown in Figs. 2 and 8 at 150. Cutting away the portion of the fold-pressing member 130 at 150 results in forming a reduced portion 152 on the fold-pressing member. The latter is so arranged in the machine that the reduced portion 152 lies adjacent the plow and the forward edge of the reduced portion 152 is oblique in a direction parallel to the edge of the material as it is curled over in the folding operation. At the same time the reduced portion 152 is made of such dimensions that when the fold-pressing member 130 is pressed upon 80 the folded over edge of the material, the reduced portion presses only a portion of the folded edge and in this manner operates to give a preliminary pressure to the fold only and not across the entire width of the

edge being folded. As the material is fed 65 forward the next step, the part which has been pressed by the reduced portion then passes under the extended portion of the fold-pressing member and the fold is pressed down across its entire width. 70

For the purpose of slitting the edge of the material being folded whenever desired at the will of the operator and without interfering with the operation of the machine, I provide a movable upper cutting knife 24 75 co-operating with a lower knife-block 23.

The upper knife 24 is fastened by a screw 156 to the upper end of a bell-crank lever 157 mounted loosely on the bearing shaft 122. The lower end of said lever 157 is 80 slotted to receive the pin 145. The knife is vibrated from the main shaft through the medium of the bell-crank lever 143, pin 145, and bell-crank lever 157.

The lower knife-block 23 is adjustably 85 mounted on a slide block 160 by means of a screw 161 passing through a slot in the knife-block. The slide block is supported in the yoke 14 and is positively held in such position that the knife-block 23 is in operative relation with the upper knife for slitting purposes. The means for holding the slide-block in operative position consists of a cam 163 in the form of a segment of a circle pivotally mounted at 164 on the yoke 14. 90 The cam is provided with a flange the edge of which serves as the cam-surface 165 adjusted to engage a depending pin 167 set in the end of the slide-block 160.

A spring 169 is provided for keeping the 100 pin 167 in positive engagement at all times with the cam face 165. In order to suspend the cutting operation without interrupting the operation of the machine and at the will of the operator, I provide treadle operated 105 means for moving the slide-block 160 toward the operator and thereby the lower cutting knife-block 23 out of cutting engagement with the upper movable knife 24.

These means consist of a lever 170 secured 110 to the cam 163 and a treadle rod 172 which may be attached to a treadle not shown. When the treadle is depressed the arm 170 is drawn downwardly turning the cam 163 and presenting the cam-surface 165 to the 115 pin 167 and the spring 169 then draws the slide-block 160 to the right, referring to Fig. 3, and moves the knife-block 23 out of operative engagement with the upper knife 24. When the pressure on the treadle is released a spring 175 returns the cam 163 to its normal position and the knife is then again in cutting engagement with the lower block 23. 120

It will be noticed that an important feature of this invention is the provision of novel means for raising the folding instrumentalities which are mounted on the upper

5 arm in order to permit work in the form of an endless band to be inserted between the upper and lower arms. This enables the machine to be employed for folding closed 10 vamps. In Fig. 7 the machine is illustrated as operating on a closed vamp at the throat, the heel portion of the vamp lying upon the work table and underneath the overhanging arm and the parts thereon. In the folding 15 operation, it is important that that portion of the work operated on by the folding instrumentalities should lie flat on the work-support in order that the edge may be folded smoothly and evenly. Any distortion of the 20 work tends to interfere with the operation of the folding instrumentalities on the work and prevents good results being secured.

25 In Fig. 7, 180 designates a closed vamp, 181 the throat of the vamp and 182 the heel portion, the latter resting upon the depressed portion of the work-table underneath the overhanging arm. In this position it will be noticed, the throat of the 30 vamp lies flat upon the work-support which enables the operator to fold over the curved edge of the vamp at the throat while it is in the flat condition and with as much ease as if the vamp was being folded while open and flat.

35 It is to be understood that my invention may be embodied in forms of construction other than that hereinbefore shown and described and it is my desire to claim the invention broadly except where specifically limited in the following claims.

What I claim is:

1. In a folding machine the combination of a work-table, an overhanging arm arranged above said work-table, feeding means 40 and a presser-foot mounted on the end of said arm and means whereby said feeding means and said presser-foot may be moved upwardly away from the work-table during the operation of the machine to permit work 45 to be inserted between the work-table and said feeding means and presser-foot into the space between the overhanging arm and the work-table; said means comprising a shaft and treadle operated means for rock- 50 ing said shaft.

2. In a folding machine the combination of a work-table, an overhanging arm arranged above said work-table, feeding means and a presser-foot mounted on the end of 55 said arm and means whereby said feeding means and said presser-foot may be moved upwardly away from the work-table during the operation of the machine, without interfering therewith and at the will of the operator, to permit work in the form of an endless band to be inserted between the work-table and said overhanging arm; said means comprising a shaft and treadle operated means for rocking said shaft.

3. In a folding machine the combination 65 of a work-table, an overhanging arm arranged above said work-table, feeding means and a presser-foot mounted on the end of said arm and means whereby said feeding means and said presser-foot may be moved 70 upwardly temporarily away from the work-table during the operation of the machine, without interfering therewith and at the will of the operator, in order to permit work in the form of an endless band to be inserted 75 between said work-table and said feeding means and presser-foot into the space between the overhanging arm and the work-table; said means comprising a shaft and treadle operated means for rocking said 80 shaft.

4. In a folding machine, the combination 85 of a work-table, an overhanging arm arranged above said work-table, folding instrumentalities arranged part on said overhanging arm and part on said work-table and means whereby such of said folding instrumentalities as are mounted on said overhanging arm may be raised at the will of the operator during and without interfering 90 with the operation of the machine to permit work in the form of an endless band to be inserted between said work-table and said overhanging arm; said means comprising a shaft and treadle operated means for rock- 95 ing said shaft.

5. In a folding machine, the combination 100 of a work-table, an overhanging arm arranged above said work-table, feeding means and a presser-foot carried on the end of said arm, means including a lift-shaft for imparting reciprocating movements to said feeding means and said presser-foot during the operation of the machine and treadle operated means for rocking said lift-shaft 105 to raise said feeding means and presser-foot away from said work-table to permit work to be inserted therebetween.

6. In a folding machine, the combination 110 with feeding, fold-turning and pressing devices of an overhanging arm carrying one or more of said devices and a work-table having a depressed portion under the said arm to facilitate the passage of the work between said arm and said work-table.

7. In a folding machine, the combination 115 of feeding, fold-turning and fold-pressing means cooperatively associated with an overhanging arm carrying said feeding means and a work-table below said arm having that portion underneath said arm depressed to facilitate the passage of work between said arm and said plate.

8. In a folding machine, the combination 120 of a work-table, an overhanging arm arranged above said work-table, means for feeding the work between folding operations, means for holding the work between

feeding operations, both of said means being carried by said overhanging arm, a lift-shaft for imparting a reciprocating movement to said feeding and said holding means and treadle operating means for rocking said lift-shaft to raise said feeding and said holding means away from said work-plate

to permit work to be passed between them and into the space inclosed between said arm and said work-plate. 10

In witness whereof I hereunto set my hand this twenty third day of June, 1916.

WILLIAM F. LAUTENSCHLAGER.
